PRESSURIZED LIQUID SPRAY GUN

John H. Studinger, Aurora, Colo., assignor to Aqua Engineering Corporation, Aurora, Colo., a corporation of Colorado

Filed Aug. 12, 1968, Ser. No. 13,104

Term of patent 14 years

Int. Cl. D23—01

U.S. Cl. D23—17

FIG. 1 is a side elevational view of a pressurized liquid spray gun;

FIG. 2 is a top plan view thereof; and

FIG. 3 is a bottom plan view thereof.

I claim:

The ornamental design for a pressurized liquid spray gun, substantially as described and shown.
